UNITED STATES PATENT OFFICE.

ISAAC LEWENTHAL, OF NEW YORK, N. Y., ASSIGNOR TO ROYAL METAL MANUFACTURING COMPANY, OF NEW YORK, N. Y., A CORPORATION OF NEW YORK.

DESIGN FOR A BELT-BODY OR SIMILAR ARTICLE.

SPECIFICATION forming part of Design No. 35,766, dated February 18, 1902.

Application filed December 21, 1901. Serial No. 86,862. Term of patent 7 years.

To all whom it may concern:

Be it known that I, ISAAC LEWENTHAL, a citizen of the United States, and a resident of the city and county of New York, borough of Manhattan, and State of New York, (whose post-office address is 120 Walker street, in said city,) have invented and produced a certain new and original Design for a Belt-Body or Similar Article, of which the following is a specification.

In the drawings forming part of this specification, Figure 1 is a front elevation of the belt-body, and Fig. 2 is a rear elevation.

The body comprises three parts, the intermediate and rectangular-shaped section 1

and the bands 2 3, having their transverse intermediate diameters greater than the intermediate section and having longitudinally-extending lines 4, indicating fullness or folds in the fabric.

Having described my invention, I claim—

The design for a belt-body or similar article, substantially as herein shown and described.

Signed in the city, county, and State of New York this 19th day of December, 1901.

ISAAC LEWENTHAL.
